[57] CLAIM

We claim the ornamental design for the three-post earthquake-resistant and absorption bridge and building support, as shown and described.

DESCRIPTION

FIG. 1 is a perspective view of a 3-post earthquake-resistant and absorption bridge and building support showing our new design;

FIG. 2 is a top plan view thereof.

FIG. 3 is a bottom plan view thereof.

FIG. 4 is an elevation view of one side thereof, the other two sides being the same; and,

FIG. 5 is an elevation view of one corner thereof, the other two corner views being the same.
